UNITED STATES PATENT OFFICE.

WARD W. LINCOLN, OF ROCK FALLS, ILLINOIS.

FOLDING WALL-RACK.

1,341,654.

Specification of Letters Patent.

Patented June 1, 1920.

Application filed October 5, 1917. Serial No. 194,856.

To all whom it may concern:

Be it known that I, WARD W. LINCOLN, a citizen of the United States, residing at Rock Falls, in the county of Whiteside and 5 State of Illinois, have invented certain new and useful Improvements in Folding Wall-Racks, of which the following is a specification.

My invention has reference to folding 10 wall racks, or that kind which are designed for the support of a number of garments in compact space. While my device is specially adapted for use in closets and presses for clothes, it is capable of being employed 15 in a variety of other places.

By the use of my invention it is possible 20 to pack several skirts, pairs of pants or other articles tightly against one of the walls of a closet or room, or against the door thereof, in such a manner that they can be readily removed or replaced, when desired.

These and other features and advantages 25 of my device will more fully appear in the following specification, reference being had to the drawings accompanying the same, in which:

Figure 1 shows my invention in vertical 30 longitudinal section, in open position. Fig. 2 is a similar view thereof, partially closed. Fig. 3 is a detail of the mechanism for operating the bars 9, in open position. Fig. 4 is a similar view, in closed position. Fig. 35 5 is a longitudinal section of a modified form of rack, in open position. Fig. 6 is a similar view, in partially closed position.

1 represents a support, having cross-pieces 2, by means of which it can be secured to a wall or other fixture. 3 is a rack, foldably connected with the support 1 by means of braces 4, extending from a central point of the rack to the upper part of the frame 1, and a brace 5, connecting the inner end of the rack with the lower end of the support. 40 The rack is provided at its ends with rigid cross pieces 6, and at intervals in the inner faces of the side-pieces of the rack are recesses 7 in which are removably held the ends of rods 8, of sufficient length to hold a 45 pair of pants, skirt or other garment folded over the same. When the rack is provided with the desired number of such garments it is tipped upwardly into a position approaching the vertical, as shown in Fig. 2. 50 To attain this position the rack is first pulled outwardly, permitting the upper end

of the brace 5 to describe a semi-circle, such end passing below the point of support of the brace. In this position the garments are brought into close proximity with one another, one in front of the other.

The relative lengths of the braces 4 and 5 is such that when the rack is in open position it will be in a horizontal plane, as shown, and in convenient position for placing articles therein or removing them therefrom. To place a garment in position in the rack one of the rods 8 is removed and the garment folded over the same, after which the rod is replaced. When the rack 70 is filled or partially filled with garments and is closed up against the support, the weight of such garments tends to retain such rack in a closed position; in fact, the greater the weight that is placed thereon, the more difficult it is to return the rack to an open position. After passing a neutral point, however, in opening the rack, the tendency 75 is equally as strong in the direction of holding the same open.

To prevent accidental release of the rods 8 when the rack is raised or partly raised, the side-pieces of the rack 3 may be provided with bars 9, slideable thereon by means of pins 10 in the rack, passing through slots 85 11 in the bars. The bars 9 are provided with a plurality of openings 12, corresponding with the recesses 7, and registering therewith when the rack is in open position, so as to permit removal of the rods 8. The 90 bars 9 are connected with the braces 4 by means of arms 13, pivotally attached at each end, the connection with the arms 4 being at a little distance from the pivotal point thereof, so that in the movement of the brace 95 with relation to the rack 3 the pivotal point of the arm describes a semi-circular movement about the brace pivot. When the rack is raised this causes a movement of the bar 9 upon the side-piece 3, bringing the openings 12 out of register with the recesses 7, and locking the ends of the rods 8 in place. When the rack is returned to a horizontal 100 position the openings 12 resume their former position, in register with the recesses 7, 105 again permitting removal of the rods.

Figs. 5 and 6 illustrate a form of my invention which is more specially adapted for use in a kitchen, for the support of towels, cloths and similar articles. This form has 110 a shorter frame 14, the ends of which are united by a cross-piece 15, by means of which

the same can be secured in place. 16 is a rack provided with a limited number of rods or rounds 17, rigidly secured in place. The rack is connected with the support 14 5 by means of braces 18 and 19, similar in character and operation to the braces 4 and 5 of the first-named form. When the rack is open the articles mentioned can be placed on the bars 17 and then the rack folded up 10 against the wall, in which position the cloths thereon are permitted to dry, if wet.

It will be obvious that my invention can be used for the support of garments in a receptacle in a store, or against the wall of 15 a store. It is also convenient for the display of neck-ties, belts and similar articles.

What I claim as my invention and desire to secure by Letters Patent of the United States, is:

20 1. A device of the class described, comprising a supporting frame, a rack foldably connected therewith and provided with a

plurality of rods removably held in place therein; and means for locking said rods in place when said rack is in any but a 25 horizontal position.

2. In a device of the class described, a supporting frame; a rack provided with a plurality of rod supporting recesses; braces connecting said rack with the upper part of 30 said frame; braces connecting the inner end of said rack with the lower end of said frame; and slide-bars provided with openings coinciding with the recesses in said rack and operatively connected with said 35 first-named braces to cause a movement of said bars when said rack is raised.

In testimony whereof I affix my signature in the presence of two witnesses.

WARD W. LINCOLN.
